UNITED STATES PATENT OFFICE.

JOHN B. PARADIS, OF MOMENCE, ILLINOIS.

CULTIVATOR-COUPING.

SPECIFICATION forming part of Letters Patent No. 239,268, dated March 22, 1881.

Application filed June 25, 1880. (No model.)

To all whom it may concern:

Be it known that I, JOHN B. PARADIS, a citizen of the United States, residing at Momence, in the county of Kankakee and State 5 of Illinois, have invented a new and useful Coupling for Cultivators, of which the following is a specification.

My invention relates to improvements in couplings for cultivators, which, while connecting the beam with the axle of the cultivator, admit of a free vertical and horizontal swinging movement of the beam or beams; and the objects of my improvements are, first, to prevent a lateral rocking of the beam, and consequently avoid a wearing upon the under side 15 of the coupling arm or bar, which would round it and gradually increase the objectionable rocking movement; second, to permit the lateral adjustment of the beam or beams toward 20 each other without destroying the direct horizontal movement of the coupling-plate or subjecting it to wear upon its edges. I attain these objects by the mechanism illustrated in the accompanying drawings, in which—

Figure 1 is a side elevation of an ordinary cultivator provided with my improved coupling; Fig. 2, a partly-sectional perspective of my coupling, showing the relative position of the parts of the coupling to each other and to 25 the beam and axle of the cultivator; Fig. 3, a modification of the coupling-bar and of the attachment of the clamping and axle plates; Fig. 4, a side elevation of said plates, with the coupling-bar in cross-section; Fig. 5, a detail 30 modification of the yokes or staples for securing the axle-plate to the axle.

Similar letters refer to similar parts throughout the several views.

A represents the axle of an ordinary cultivator.

B is a rectangular-shaped axle plate or block, having at or near its ends staples a^1 , to pivotally secure it to the axle. These staples are made adjustable to compensate for wear by 40 means of screw-threaded ends and nuts, as shown in Fig. 4; but instead thereof I may use a flat spring-hook, a^2 , the shank of which forms an extension of the axle-plate, and its hook a seat for a screw-threaded bolt, a^3 , upon 45 said plate, which bolt passes through the hook and a block of wood, a^4 , intermediate the hook and plate, and is provided with a nut, a^5 , upon

its outer end, as shown in the modification in Fig. 5. The axle-plate, when taken with the staples, forms an open frame, adjustably pivoted at its ends. 55

Resting upon the axle-plate is a flat coupling-bar, C, consisting of straight arm c and curved arm c' , which arms, when taken together, give the bar in outline the appearance 60 of the letter J, as clearly shown in Fig. 2 of the drawings. The coupling-bar C is perforated from face to face at the intersection of the arms c c' , and is pivotally secured to the axle-plate by a U-shaped bolt, D, one arm, d , of 65 which passes through a perforation near the outer end of said plate and through the perforation in the coupling-bar, and the other arm, d' , through a perforation near the center of length of the axle-plate, where it passes through 70 a block, E. This block is slightly thicker than the coupling-bar, and forms a support for a plate, F, between which and the axle-plate the coupling-bar is loosely held or clamped, so that the bar may move about its pivot, but not 75 rock, its curved arm c' moving around the block, as indicated by dotted lines in Fig. 2, when the beam G, to which the straight arm c is bolted, is swung around to shift the cultivator-blades. 80

From the above-described construction it will be seen that while with my coupling a cultivator may have the requisite vertical and horizontal movements it cannot be twisted, and consequently strained, by a rocking movement of its beam, by reason of the faces of the curved arm near its outer edge, which are opposite and some distance from the pivot of the coupling-bar, impinging against either the clamping or axle plate. If the coupling-bar 85 had no horizontal movement an arm extending at a right angle from the straight arm c , between and coinciding with the length of the clamping and axle plates, would have the same function. In other words, the curved arm operates as the long arm of a lever having the play of its free end limited, the pivot representing the fulcrum, and the width of the straight arm c the short arm of the lever. As 90 the comparative length of the long arm is so much greater than the short arm, the slight vertical movement which the former may have between the plates will have no perceptible effect upon the short arm, and consequently 95 100

not only will a rocking of the beam to which the short arm is connected be avoided, but a straining or bending of the pivot be prevented. Furthermore, the absence of a rocking movement avoids any tendency which the coupling-bar would otherwise have to wear rounding or uneven upon its under surface, and thereby aggravate the rocking above referred to.

Instead of the curved arm upon the coupling-bar, as shown in Fig. 2, said bar may be made solid, as shown in Fig. 3, and the clamping plate and block be bolted at the outer end of said plate to the axle-plate, the pivot of the coupling-bar maintaining the same relative position to the axle-plate as before described—*i. e.*, toward the outer end of the axle-plate.

A lateral adjustment of the beam or beams toward or from the center of length of the cultivator-axle may be made in two ways: first, by providing the clamping and axle plates with a corresponding series of perforations, similar to those already indicated, into which the arms d d' of the yoke D may be shifted; and, second, by reversing the position of the coupling-bar—*i. e.*, by turning said bar over, so as to place the curved arm upon the outside of the pivot d , which also necessitates the removal of the block to said pivot, then pivoting the bar upon the pivot d' .

Among the advantages derived from coup-

lings such as I have described are, first, simplicity and durability of parts; second, non-liability of the accidental displacement or detachment of the parts; third, the adaptability of said couplings to ordinary cultivators; and, 35 fourth, that by reason of the absence of a rocking movement of the beam straighter and more even depth of furrow is maintained, which results in less liability of injuring the material under cultivation.

Having thus described my invention, what I claim, and desire to secure by Letters Patent, is—

1. In a cultivator-coupling, the combination, with the axle-plate and the clamping-plate, of 45 a J-shaped coupling-bar, having its straight arm secured to the cultivator-beam and pivoted near one end of the axle-plate, said bar, with its curved extension, moving and guided between the axle and clamping plates, substantially as described and shown.

2. The combination of the coupling-bar C with the axle-plate B, yoke D, block E, and removable clamping-plate F, substantially as described, and for the purpose set forth.

JOHN B. PARADIS.
